GASOMETER CONSTRUCTION

Hans Weichsel, Webster Groves, Mo., assignor to
 Wagner Electric Corporation, St. Louis, Mo., a
 corporation of Delaware

Application May 27, 1937, Serial No. 145,090

2 Claims. (Cl. 220—85)

My invention relates to gasometer apparatus for use with transformer and other tanks in which a supply of inert gas is to be maintained. In my co-pending application Serial No. 144,321, filed May 22, 1937, I have described and claimed a gasometer construction for this purpose.

Fig. 1 is a cross section of the gasometer apparatus with the parts in place for shipment.

Fig. 2 is a cross section of a modification.

10 The present application pertains to constructional features for the purpose of placing an apparatus of this kind in condition for safe shipment. As described in said co-pending application and as is shown by the drawing accompanying this application, the gasometer comprises a flexible bag element 1 and a weight element 2 carried on the top of the bag and by means of which the desired inert gas pressure is maintained in the gas containing space of the transformer tank, which space communicates with the gasometer chamber through pipe 3. In gasometers for transformer casings of substantial size the weight element 2 may weigh a hundred pounds or more and means must be provided 15 whereby the apparatus can not only be assembled in the factory in form ready for service but can be shipped without danger of the weight element injuring or destroying the flexible bag.

In accordance with my invention I provide a 20 ring 4 positioned, as shown, in the weight element and having an inclined inner surface, this ring being secured to the weight element by removable bolts 5. The top casing portion 6 of the gasometer is provided with spaced downwardly extending stop elements 7 which, in use on the gasometer, limit the upward movement of the bag and weight. These stops are so positioned that the lower ends will be received in the smallest inner diameter of positioning ring 4. A clamping 25 rod 8 is in threaded engagement with the center of the weight, extends upward through the casing cover 9 and provides means for firmly holding the inner surface of the bottom of the weight against stop elements 7 by tightening nut 10.

40 45 With the means above described, the weight element may be firmly anchored for shipment in a position with normal clearance between its

wall and the wall of the casing whereby there can be no vertical or lateral movement during shipment. Upon installation, the gasometer can be put into operation by merely removing nut 10, although it would ordinarily be preferable to 5 also remove clamping rod 8. The ring 4 can be made in sections whereby it can also be removed through the top opening in the casing if for any reason it is desired to lighten, to that extent, the weight operative on the flexible bag forming 10 the top of the gasometer gas chamber.

Figure 2 illustrates a modification in which a cylindrical stop element 11 is substituted for the spaced stop elements 7 in Figure 1.

Having fully described my invention, what I 15 claim as new and desire to secure by Letters Patent of the United States is:

1. A gasometer comprising a flexible bag element and a weight element thereon, a casing enclosing said bag element and weight, abutment means affixed to the upper part of the casing and projecting downwardly therefrom, means on the weight element cooperating with the abutment means to prevent lateral movement of the weight, and a clamping element connected to the weight 20 element to maintain the abutment means in cooperative relation with said means on the weight element, said clamping element being releasably secured to the casing.

2. A gasometer comprising a flexible bag element and a weight element thereon, a casing enclosing said bag element and weight, abutment means affixed to the upper part of the casing and projecting downwardly therefrom, an annular ring secured to the upper surface of the weight 30 element and embracing the lower end of the abutment means when the weight is in its uppermost position, the upper portion of the inner surface of the ring element being tapered and said ring and abutment means cooperating to prevent lateral movement of the weight, and a clamping rod 35 connected to the center of the weight element to maintain the abutment means and ring in cooperative relation, said rod being releasably secured to the top of the casing.
